UNITED STATES PATENT OFFICE

FRANCIS P. ELLSWORTH, OF NEW YORK, N. Y.

SHOE LACE FASTENING DEVICE

Application filed January 14, 1931. Serial No. 508,585.

The present invention relates to a shoe lace fastening device, and has for an object to provide a device of this character by means of which the shoe lace may be quickly drawn tight or loosened, without the necessity of manually tying and untying a bow-knot, and which will furthermore tightly hold the lace against accidental loosening. Another object is to provide a fastening device which can be permanently connected to the lace so that it will not become misplaced, and which may be operated with facility. It is further proposed to provide a fastening device which will be simple and inexpensive to manufacture, neat and inconspicuous in appearance, and will permit the tightened and fastened shoe lace to have the appearance of the usual shoe lace with a properly and evenly tied bow-knot. While the invention is illustrated and described with reference to a shoe lace it will be obvious that it may be used with lacing for any purpose.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a plan view of the device in its operative relation with a shoe lace, and showing the contiguous portion of the shoe.

Fig. 2 is an enlarged plan view in the normal operative position, but disengaged from the shoe lace.

Fig. 3 is a side elevation.

Fig. 4 is a sectional view taken along the line 4—4 of Fig. 2.

Fig. 5 is a side elevation showing the loosened position of the fastener.

Fig. 6 is a diagrammatic view showing an end view of the fastener with the shoe lace tightened and in fastened relation.

Fig. 7 is a similar view showing the device unfastened and the shoe lace loosened.

Similar reference characters indicate corresponding parts throughout the several figures of the drawings.

Referring to the drawings the shoe lace fastener according to the exemplary embodiment illustrated, comprises a base member 10 to one end of which is hinged a clamping member 11, the hinge pin 12 being engaged through aligned passages formed in inter-engaging cylindrical enlargements 13 and 14 formed on said base and clamping members respectively. A raised platform portion 15 is provided on the base at the open end, forming a recess 16 between said platform and the hinge, and a recess 17 is provided on the under side of the clamping member in position to engage upon said platform, a downwardly projected portion 18 being provided between said recess and the hinge and disposed within the recess 16 in the closed position, as indicated in Figs. 3 and 4, with its flat surface spaced from the flat surface of the recesses. The opposed flat surfaces of the recess 16 and projection 18 are forced with leather, or other suitable material, as at 19 and 20, to prevent cutting or smashing of the lace clamped therebetween, and as will hereinafter more fully appear.

The platform end 15 of the base is provided with a threaded opening 21 in which a post 22, threaded at its lower end, is removably and adjustably screwed, and which extends upwardly through an opening 23 in the clamping member with sufficient clearance to permit relative swinging of the clamping member, as indicated in Fig. 5.

A plate 24 of substantially the same plan outline as the clamping member, and having an opening 25 for the post 22, registering with the opening 23, is secured to the upper side of said clamping member by screws 26 disposed at each side of the opening 25. Opposed recesses 27 and 28 are provided in the clamping member 11 and plate 24 and are preferably faced with leather, or other suitable material, as at 29 and 30, with the opposed surfaces of the facings slightly spaced apart. The shoe lace ends are adapted to be secured between these faces, as will presently more fully appear. As such ends are permanently secured and not subject to movement, the leather facings may be dispensed with if desired.

A cam lever 31, bifurcated as at 32, is mounted on the post 22 by means of a hinge pin 33, and is provided at each side of the post with cam projections 34 adapted in the closed position as indicated in Figs. 3, 4 and 6 to bear upon the upper surface of the plate 24 and tightly clamp the clamping member against the base member, and in the open position, as indicated in Figs. 5 and 7, to permit the clamping member to be raised. The lever 31 bears upon the end of the plate 24 in the closed position, being maintained in such position by the pressure on the off-center cam surfaces, and the end of the lever projects slightly beyond the plate to permit it to be readily engaged with the finger to move it to open position. The screws 26 are normally disposed beneath the lever 31 to conceal them, but may be made accessible, for loosening the plate 24, by turning the lever 31 and post 22 at a right angle to the normal position. The degree of clamping pressure of the clamping member may be adjusted by turning the post 22 by means of the cam lever to either raise or lower the axis of said lever with respect to the base member.

The operation is as follows:—

The ends of the lace 26 are first carried in opposite directions through the lower space 30 between the base member 10 and the clamping member 11, and then in opposite directions through the upper space between the clamping member and the plate 24, which is first loosened for this purpose by unscrewing the screws 26. The ends are thereupon permanently clamped between the clamping member and the plate by tightening the screws 26. In order to tighten the lace the cam lever is raised as shown in Fig. 7, and the 40 loops of the lace are pulled outwardly until the lace is tight, whereupon the cam lever is pressed down, clamping the lace tightly between the clamping member and the base member. In order to loosen the lace the cam 45 lever is raised and the device pulled upwardly, the lace sliding freely between the clamping member and the base member, while the lace ends are permanently held. To tighten the lace the loops are preferably grasped 50 by the thumb and first finger of each hand and pulled away from the fastening device and when sufficiently tight are held with the thumbs while the cam lever is pressed down with the first finger of one hand. The lace 55 is thus held against slipping and loosening, and presents the appearance of a properly and evenly tied bow-knot.

I have illustrated and described a preferred and satisfactory embodiment of my invention, but it will be obvious that changes may be made therein, within the spirit and scope thereof as defined in the appended claims.

Having thus described my invention what

I claim and desire to secure by Letters Patent is:—

1. In a lace fastening device of the character described, means for releasably holding portions of a lace spaced from each end, and means for fixedly securing the end portions of the lace. 70

2. In a lace fastening device of the character described, means for releasably holding portions of a lace spaced from each end, and adapted to permit sliding movement of said portions upon release, and means for fixedly securing the end portions of the lace. 75

3. In a lace fastening device of the character described, adjustable means for releasably and removably holding portions of a lace spaced from each end, and adjustable means for fixedly and removably securing the end portions of the lace. 80

4. In a lace fastening device of the character described, clamping means for releasably holding portions of a lace spaced from each end, means operable to tighten and loosen said clamping means with respect to said lace, and means for fixedly securing the end portions of the lace. 85 90

5. In a lace fastening device of the character described, clamping means for releasably holding portions of a lace spaced from each end and comprising relatively movable parts, means adapted to clamp and release said parts with respect to each other, and means for fixedly securing the end portions of the lace. 95

6. In a lace fastening device of the character described, clamping means for releasably holding portions of a lace spaced from each end and comprising relatively movable parts, adjustable means adapted to clamp and release said parts with respect to each other, to be adjusted to vary the degree of clamping pressure, and means for fixedly securing the end portions of the lace. 100 105

7. In a lace fastening device of the character described, clamping means for releasably holding portions of a lace spaced from each end and comprising relatively movable parts, a cam lever carried by one of said parts adapted to clamp and release said parts with respect to each other, and means for fixedly securing the end portions of the lace. 110 115

Signed at Saranac Lake, Franklin County, State of New York, this 30 day of December, 1930.

FRANCIS P. ELLSWORTH.
